[57] CLAIM

The ornamental design for a needle package, as shown.

DESCRIPTION

FIG. 1 is a front elevational view of a needle package showing my new design;

FIG. 2 is a rear elevational view;

FIG. 3 is a rear perspective view on a reduced scale in a partially open position; and

FIG. 4 is a view similar to FIG. 3 in a more fully open position.

FIG 1

FIG 2

FIG. 3

FIG. 4
